UNITED STATES PATENT OFFICE.

ANNIE A. R. ANDERSON, OF MINNEAPOLIS, MINNESOTA.

DESIGN FOR A SOAP-DISH.

49,414.

Specification for Design.

Patented July 25, 1916.

Application filed February 11, 1916. Serial No. 77,812. Term of patent 3½ years.

To all whom it may concern:

Be it known that I, ANNIE A. R. ANDERSON, a citizen of Sweden, residing at Minneapolis, in the county of Hennepin and State of Minnesota, have invented a new, original, and ornamental Design for a Soap-Dish, of which the following is a specification, reference being had to the accompanying drawings, forming part thereof.

The figure is a perspective view of a soap-dish illustrating my new design.

I claim:

The ornamental design for a soap-dish, as shown.

ANNIE A. R. ANDERSON.

Witnesses:

ERIC WERNBORG,
A. A. KANE.
